US00D913923S

(12) **United States Design Patent** (10) Patent No.: **US D913,923 S**
You et al. (45) Date of Patent: **** Mar. 23, 2021**

(54) **ENERGY STORAGE SYSTEM**

(71) Applicant: **LG ELECTRONICS INC.**, Seoul (KR)

(72) Inventors: **Hyunhee You**, Seoul (KR); **Yongho Lee**, Seoul (KR)

(73) Assignee: **LG ELECTRONICS INC.**, Seoul (KR)

(**) Term: **15 Years**

(21) Appl. No.: **35/508,060**

(22) Filed: **Jun. 7, 2019**

(80) **Hague Agreement Data**

Int. Filing Date: **Jun. 7, 2019**

Int. Reg. No.: **DM/203844**

Int. Reg. Date: **Jun. 7, 2019**

Int. Reg. Pub. Date: **Dec. 13, 2019**

(30) **Foreign Application Priority Data**

Dec. 11, 2018 (KR) 30-2018-0058215

(51) **LOC (13) Cl.** **13-02**

(57)

CLAIM

The ornamental design for an energy storage system, as shown and described.

DESCRIPTION

1. Energy storage system

1.1 : Perspective

1.2 : Rear perspective view

1.3 : Front

1.4 : Back

1.5 : Left

1.6 : Right

1.7 : Top

1.8 : Bottom

(Continued)

The broken lines indicate portions of the article that form no part of the claimed design.

1 Claim, 8 Drawing Sheets
